United States Patent Office

Des. 211,758
Patented July 23, 1968

211,758

PHOTOMETRIC INSTRUMENT OR THE LIKE

Robert W. Mitchell, St. Joseph, and Robert L. Gallup,
Berrien, Mich., assignors to Heath Company, Benton
Harbor, Mich., a corporation of Delaware

Filed Feb. 27, 1967, Ser. No. 5,967

Term of patent 14 years

(Cl. D61—1)

Fig. 1

Fig. 2

Fig. 3

Fig. 4

FIG. 1 is a perspective view of a photometric instrument incorporating our new design;

FIG. 2 is a side elevational view thereof;

FIG. 3 is a front elevational view thereof; and

FIG. 4 is a top plan view thereof.

We claim:

The ornamental design for a photometric instrument or the like, substantially as shown.
